UNITED STATES PATENT OFFICE.

FREDERIC M. BURDITT, OF NEWTON CENTER, MASSACHUSETTS.

RAZOR STROP.

Application filed March 13, 1922. Serial No. 543,258.

To all whom it may concern:

Be it known that I, FREDERIC M. BURDITT, a citizen of the United States, residing in Newton Center, in the county of Middlesex and State of Massachusetts, have invented an Improvement in Razor Strops, of which the following description, in connection with the accompanying drawings, is a specification, like characters on the drawings representing like parts.

This invention relates to a strop for razors, knives and like cutting instruments, and has for its object to provide a superior strop for the purpose specified. In the preferred embodiment of the invention, a strap is connected with a supporting frame having expandable and contractible members with which the strap co-operates to be supported thereby, and by means of which the strap may be placed under different tensions to suit the user.

It is also preferred to use a leather and a canvas strap located on opposite sides of the supporting frame, and to provide a common actuating device for the expandable and contractible members co-operating therewith.

The expandable and contractible members are constructed and arranged so as to place the straps under tension when said members are expanded, and to relieve the straps from tension when contracted, in which latter condition said members are brought close to the supporting frame and substantially parallel therewith, so that the strop may be brought into a compacted condition for carrying in a traveling bag or for shipping in a carton.

These and other features of this invention will be pointed out in the claims at the end of this specification.

Fig. 1 is a plan view with parts broken away of a razor strop embodying this invention, the upper strap being omitted.

Fig. 2, a longitudinal section on the line 2—2, Fig. 1.

Fig. 3, a side elevation of the supporting frame shown in Fig. 2, with its expandable and contractible members in their collapsed condition.

Fig. 4, a section on the line 4—4, Fig. 5.

Fig. 5, a side elevation of the strop with the straps under tension and in condition for use.

Fig. 6, a plan of the supporting frame shown in Fig. 1.

Fig. 7, a cross section on an enlarged scale, taken on the line 7—7, Fig. 5, and

Fig. 8, a detail of one of the nuts to be referred to.

In the present instance is shown a preferred construction of razor or like strop, in which two straps *a*, *b*, preferably of leather and canvas respectively, are connected together at their opposite ends to form an endless band or strap, which is connected with a supporting frame provided with expandable and contractible members located within the endless strap and co-operating with members *a*, *b*, thereof, to place them under tension or to relieve them from tension as will be described.

The supporting frame herein shown is composed of two metal plates or bars 10, 12, preferably of aluminum, which are secured together by rivets *c* (see Fig. 4) or otherwise and are provided with substantially central longitudinally extended concaved portions, substantially semicircular in cross section, which co-operate to form a tubular housing 13 for a screw-threaded rod 14, which is extended through suitable holes in the endless band and is provided at one end with a head 15 having a flange 16 and at its other end with a handle 17 having a ferrule 18, which bears against a metal washer 19 loosely mounted on the housing 13.

Each strap *a*, *b*, has co-operating with it near the opposite ends of the supporting frame, expandable and contractible members preferably made similar to a toggle. The expandable and contractible member co-operating with the strap *a* at one end of the latter comprises two members 20, 21, pivotally connected together by the pin 22, the member 20 being pivotally connected by the pin 23 with the plate or bar 10, and the member 21 being pivotally connected by the pin 24 with a nut 25, which is mounted on the screw rod 14.

The expandable and contractible member co-operating with the strap *a* at its other end comprises members 26, 27, pivotally connected together by the pin 28, the member 26 being pivotally connected with the plate or bar 10 by the pin 29, and the member 27 being pivotally connected by the pin

30 with a nut 31, which is mounted on the screw rod 14.

The strap *b* has co-operating with it expandable and contractible members of like 5 construction and numbered the same.

It will thus be seen that the expandable and contractible members practically form toggles, each comprising two members which are pivoted together and one of which is 10 anchored to the supporting frame and the other of which is connected with a nut which is movable toward and from the anchored end, so as to move the free end of the anchored member toward and away from 15 the screw rod 14.

In the collapsed condition of the strop, the expandable and contractible members assume a position substantially parallel with the screw rod 14 in proximity thereto as 20 represented in Fig. 3, and in the expanded condition of the strop, said members assume inclined positions with relation to said screw rod (see Figs. 2 and 5).

When the strop is in its extreme collapsed 25 condition, the expandable and contractible members assume the position shown in Fig. 3, in which the nuts 25, 31, are removed from the furthest from the anchored ends 23, 29 of the said members.

30 By turning the screw rod 14 in the proper direction, the nuts 25, 31, are caused to move on the screw rod toward the anchored ends 23, 29 of the expandable and contractible members, and the members 21, 27 push the 35 members 20, 26, up into an inclined position and cause the members 20, 26, to engage the straps *a*, *b*, and place them under tension, the amount of which can be governed by the screw rod 14.

40 By turning the screw rod 14 in the opposite direction, the nuts 25, 31, are caused to travel on the screw rod 14 away from the anchored ends 23, 29, of the toggles or expandable members, and when said nuts are 45 moved into their extreme position shown in Fig. 3, the straps *a*, *b*, are relieved from tension and can be brought close to the supporting frame for packing or shipping purposes.

50 It will be observed that by means of the screw rod 14, the expandable members may be placed in proper position to put the straps *a*, *b*, under the tension desired by the operator.

55 In the present instance, the strop is represented as provided with two straps *a*, *b*, one of leather and the other of canvas or other

suitable material and while it may be preferred to use two straps and two sets of expandable and contractible members co-operating therewith, it is not desired to limit the invention in this respect, as it is evident that one of the straps and its co-operating expandable members may be omitted if desired. 60 65

Claims.

1. In a strop for razors, knives and like instruments, in combination, a supporting frame, an endless strap connected therewith, a screw-rod mounted to turn in said supporting frame, nuts mounted on said screw rod, toggles located between said supporting frame and said endless strap and having members pivotally anchored to said supporting frame and other members pivotally connected with said nuts. 70 75

2. In a strop for razors, knives and like instruments, in combination, a supporting frame, a strap connected therewith, a screw rod mounted to turn in said supporting frame, nuts mounted on said screw rod and expandable and contractible members comprising toggles anchored at one end to said supporting frame and connected at their other end to said nuts to be moved therewith to cause the anchored members of said toggles to place the said strap under tension. 80 85

3. In a strop for razors, knives and like instruments, in combination, a supporting frame, a strap connected therewith, a screw rod mounted to turn in said supporting frame, a nut mounted on said screw rod to be moved longitudinally thereof by rotation of said screw rod, and expandable and collapsible means engaging said strap and actuated by said nut for placing said strap under tension. 90 95

4. In a strop for razors, knives and like instruments, in combination, a supporting frame, an endless strap connected therewith, expandable and contractible members located on opposite sides of the supporting frame cooperating with said strap to support the material length thereof between the same, and a common actuating device carried by the supporting frame and operatively connected with said expandable and contractible members for laterally moving the strap to stretch it between said expandable and contractible members. 100 105 110

In testimony whereof I have signed my name to this specification.

FREDERIC M. BURDITT.
